Primary Examiner — Patricia Palasik(74) *Attorney, Agent, or Firm* — Westerman, Hattori, Daniels & Adrian, LLP(57) **CLAIM**

The ornamental design for a three dimensional printer, as shown and described.

DESCRIPTION

FIG. 1 is an isometric view of a three dimensional printer showing our new design.

FIG. 2 is a front elevational view of the three dimensional printer thereof.

FIG. 3 is a rear elevational view of the three dimensional printer thereof.

FIG. 4 is a left side elevational view of the three dimensional printer thereof.

FIG. 5 is a right side elevational view of the three dimensional printer thereof.

FIG. 6 is a top plan view of the three dimensional printer thereof; and,

FIG. 7 is a bottom plan view of the three dimensional printer thereof.

The broken lines in the drawings depict unclaimed environmental subject matter.

1 Claim, 7 Drawing Sheets(56)
